PILE REGULATOR

Bascum O. Austin, Lima, Ohio, assignor to Westinghouse Electric Corporation, East Pittsburgh, Pa., a corporation of Pennsylvania

Application August 17, 1948, Serial No. 44,776

8 Claims. (Cl. 201—51)

1

This invention relates to pile regulators, and in particular to pile regulators of the lightweight aviation type.

Lightweight carbon pile regulators have recently been developed for use in airplanes, buses, automobiles and the like. Such regulators are exemplified by the structure shown and claimed in Patent No. 2,268,718, issued January 2, 1942 to Newton. Generally, such regulators comprise a stack of discs of resistance material, the pressure of which is controlled by an electromagnet having an armature mounted on a special spring construction which works between a sloped abutment surface and the stack.

In commercial practice, it has been difficult to maintain stability in a regulator of the type exemplified by the Newton patent, as the special mounted armature assembly is detrimentally affected during operation of the regulator by heat conducted from the stack. Further, the abutment member seats against the electromagnet being held in position only by the pressure of the spring of the armature assembly with the result that under operating conditions involving vibration, the abutment member vibrates and varies the bias of the spring and thereby causes an unstable operation of the regulator.

An object of this invention is to provide, in a pile regulator having an armature assembly including a spring therefor, for preventing the direct transfer of heat and electricity from the pile to the armature and spring under operating conditions for the regulator.

Another object of this invention is to provide a pile regulator having a spring mounted armature assembly working between an abutment member and the pile to control the pressure thereof with a housing which cooperates with the abutment member to prevent vibration thereof.

A further object of this invention is to provide, in a pile regulator having a spring mounted armature assembly which works between an abutment member and the pile, for firmly holding the abutment member to prevent vibration thereof and to also prevent the direct transfer of heat and electricity from the pile to the spring.

Other objects of this invention will become apparent from the following description when taken in conjunction with the accompanying drawing, in which:

Figure 1 is a view in side elevation and partly in section illustrating a pile regulator embodying the teachings of this invention, and

Fig. 2 is a view in section greatly enlarged of the armature assembly of the regulator illustrated in Fig. 1.

2

Referring to the drawing and in particular to Fig. 1 thereof, this invention is illustrated by reference to a pile regulator 10 formed of a stack 12 of discs 14 of resistance material, such as carbon, and an electromagnet assembly 16 disposed to control the pressure on the stack 12.

As illustrated in Fig. 1, the stack 12 is disposed between a relatively fixed pressure plate 18 of carbon or the like and a movable pressure plate 20, also of carbon, being encased in a metallic tubular housing 22. The housing 22 is of any suitable metal being preferably of Invar, a 36% nickel-iron alloy, which has substantially zero coefficient of thermal expansion. The outer surface 24 of the housing 22 is preferably roughened as by knurling, fluting or otherwise forming ribs or grooves thereon to aid in securing a plurality of cooling fins 26 thereon. The cooling fins 26 are preferably of aluminum and are disposed about the housing 22 in spaced relation lengthwise of the housing for dissipating heat which is developed in the stack 12 during an operation of the regulator. As a general rule, the cooling fins 26 are independently mounted one from the other depending upon their interlocking relation with the surface of the housing 22 for maintaining them in operative relation on the housing. The fins 26 are preferably formed as by casting the aluminum in position with respect to the housing 22.

As illustrated, the terminal fin 26' at the end of the stack adjacent the fixed pressure plate 18 is formed as an integral unit with the adjacent fin 26, a common hub 30 being formed therebetween for strengthening the support of the terminal fin on the housing. This is done in order to facilitate mounting an end plate 32 to the terminal fin 26' by any suitable means, such as screws (not shown), a washer 34 of insulation being disposed between the terminal plate 32 and the terminal fin 26'. An adjustable nut 36 is disposed in threaded engagement with the plate 32 for receiving the end of the pressure plate 18 and for initial adjustment of the pressure on the stack 12.

At the opposite end of the stack 12, the terminal fin 26'' is formed simultaneously with a section 38 of a sectionalized housing for the electromagnet 16. Thus the section 38 and the terminal fin 26'' are formed with a common hub 40 therebetween, the hub 40 being securely interlocked with the roughened surface of the housing 22 to provide a strong support for the section 38 of the sectionalized housing for the electromagnet 16. The section 38 of the housing is preferably of a cup-shape form for encompassing the armature assembly 42 of the electromagnet 16, a shoulder

flange 44 being provided internally of the section 38 about the side wall thereof a predetermined distance from the ends of the section 38. The purpose of the shoulder flange 44 will be explained more fully hereinafter.

As illustrated, the electromagnet 16 is of the usual construction having an iron-core magnetic housing formed of a base-plate 48 with lugs 48 disposed in spaced relation thereabout, the side wall member 50 and end pole pieces 52 with an adjustable core member 54. The energizing winding 56 of the electromagnet is disposed about the core member 54 within the section of the sectionalized housing formed by the magnetic housing for the electromagnet being insulated from the magnetic housing and the core member in any suitable manner.

The armature assembly 42 is disposed to cooperate with an abutment member 58 for controlling the pressure applied to the stack 12. As more clearly shown in Fig. 2 of the drawing, the abutment member 58 comprises a circular ring having one surface 60 thereof sloped inwardly from adjacent the outer edge of the abutment member 58 towards the central opening of the ring thereby forming mutually inclined surfaces on the one side or face of the abutment member. The outer edge of the one face of the ring member which carries the sloped surface 60 is formed with a flat surface 62 for cooperating with the shoulder flange 44 of the section 38 of the sectionalized housing, as will be explained fully hereinafter. The opposite side of the abutment member 58 is also provided with a flat surface 64 adjacent its outer edge, the surfaces 62 and 64 preferably being parallel.

The armature assembly 42 includes a circular armature member 66 disposed centrally of the abutment member 58 and disposed for movement in the central opening thereof. The armature 66 carries a diaphragm 68 of copper or the like which extends outwardly therefrom along one side of the abutment member 58, the outer edge of the diaphragm 68 terminating on the flat surface 64 of the abutment member 58. As illustrated, the armature 66 also is disposed to carry a spring member 70 and the components for mounting the spring member.

The spring member 70 is of any suitable metal being preferably of a single thickness and of star form (not shown), the rays or fingers of the star extending beyond the armature 66 to seat against the sloped surface 60 of the abutment member 58. The spring member 70 may be formed with the rays or fingers of the spring fixed at a predetermined angle with respect to the sloped surface 60 of the abutment member, as illustrated in the Newton Patent No. 2,268,718, or may have a predetermined angle imparted thereto by other means such as is disclosed in the copending application Serial No. 44,598 (now Patent No. 2,488,455 issued November 15, 1949) of O. C. Walley, filed simultaneously herewith, it being understood that the angle of the spring 70 with respect to the sloped surface 60 of the abutment member 58 will determine the load-deflection curve of the electromagnet. In the embodiment illustrated, in order to mount the spring 70 on the armature 66, washers 72 and 74 are disposed on opposite sides of the spring 70, so that the spring 70 will be firmly held in a required position when the components are secured together. As illustrated, each of the diaphragm 68, the spring member 70 and the washers 72 and 74 is provided with a central opening therein, so that

when the components named are in aligned relation, an opening is formed for receiving an end of a cylindrical sleeve 76 of ceramic material, whereby an end of the sleeve 76 seats against the armature 66 and the other end of the sleeve 76 is disposed to receive an end of the movable pressure plate 20 and thereby carry the pressure plate in its operative relation with respect to the stack 12. The sleeve 76 may be of any suitable ceramic material, such as porcelain or glass or any burnt clay or refractory product which has good heat and electrical insulating characteristics. The end of the sleeve 76 disposed to carry the movable pressure plate 20 is also provided with a slot 78 for receiving a conductor 80 (illustrated in Fig. 1) which is electrically secured to the pressure plate.

In order to maintain the cylindrical sleeve 76 in assembled relation with respect to the other components of the armature assembly 42, the sleeve 76 is provided with a shoulder 82 for receiving the inner edge of a ring flange 84 which is disposed to seat upon the washer 74 and on the shoulder 82. A plurality of spaced screws 86 are disposed in spaced relation through the components forming the armature assembly for securing the armature 66, the diaphragm 68, the spring 70, the washer members 72 and 74 and the plate 84 together as an integral unit with the cylindrical sleeve 76 carried thereby, the abutment member 58 being disposed between the extension of the diaphragm 68 and the ends of the spring 70.

When the armature assembly 42 is disposed within the sectionalized housing for the electromagnet 16, the abutment member 58 tends to seat upon the magnetic housing for the electromagnet and when the sections of the housing are assembled and secured as by means of a plurality of spaced bolts 88, the shoulder 44 of the section 38 of the housing seats against the flat surface 62 of the abutment member to tightly hold the abutment member 58 in its mounted position and to prevent vibration thereof. As illustrated, the abutment seats upon the edge of the diaphragm 68, the diaphragm being held between the pole piece 52 of the magnetic housing for the electromagnet and the flat surface 64 of the abutment. Thus since the abutment member 58 is firmly held between the sections of the sectionalized housing, the armature assembly 42 will not be detrimentally affected by any vibrations or movement of the abutment member 58.

The regulator of this invention functions in the normal manner, in that the pull of the electromagnet on the armature 66 is in opposition to the force of the spring 70 for controlling the pressure applied through the movable pressure plate 20 to the stack 12. However, since the sleeve 76 between the pressure plate 20 and the armature 42 and the spring 70 is of a ceramic material, the sleeve 76 constitutes a heat dam to prevent any direct transfer of heat from the stack 12 and the plate 20 to the armature 66 and the spring 70. At the same time perfect electrical insulation is also provided by the sleeve 76. Thus the armature assembly is unaffected by heat developed in the stack and the characteristics of the different components forming the armature assembly 42 will not change by reason of exposure to heat.

By eliminating the possibility of damage to the armature assembly 42 or adverse effects thereon by reason of a direct transfer of heat thereto and by firmly holding the abutment member 58 in assembled relation with respect to

the other components of the regulator, a very stable operation of the regulator can be obtained. Further, by utilizing the sleeve 16 of ceramic material which is substantially unaffected by heat, it has been possible to shorten the distance between the armature 66 and the movable pressure plate 20, thereby minimizing side thrust on the discs 14 of the stack 12 to thereby reduce friction in the stack 12. The components of the assembly are formed of standard elements and the structure of this invention can be readily reproduced.

Although reference has been made hereinbefore with respect to the diaphragm 68 for effecting damping during the operation of the electromagnet, this structure is disclosed in Patent No. 2,408,188, issued September 24, 1946 to B. O. Austin and of itself forms no part of this invention. Likewise, the sectionalized housing for the electromagnet and the fin structure for the regulator is broadly disclosed and claimed in the copending application of J. D. Miner, Jr. et al., Serial No. 44,597, filed simultaneously herewith. However, the means for preventing vibration of the abutment member as disclosed in this application is distinct from any of the claimed subject matter of the identified Miner et al. application.

I claim as my invention:

1. In a pile regulator having a stack of discs of resistance material and an electromagnet disposed for operation to control the pressure applied to the stack, the combination comprising, a circular abutment member having a central opening therein and having at least a portion of one of its surfaces inclined inwardly from adjacent its outer edge towards the central opening, an armature assembly including an armature disposed in the central opening of the abutment member, a diaphragm disposed to be carried by the armature and extending outwardly therefrom along the other side of the abutment member to adjacent the outer edge thereof, a sleeve of ceramic material disposed between the armature and the stack, a spring member disposed to be carried by the armature with an end of the spring member extending therebeyond along said one surface of the abutment member to seat against the inclined surface thereof, means for securing the spring member, diaphragm, sleeve and armature together as an integral assembled unit with the abutment member disposed between the diaphragm and the spring member, a sectionalized housing for the electromagnet, one section of the housing being carried at an end of the stack and being disposed to encompass the armature assembly and abutment member, and a flange carried internally of said one section disposed to seat against the outer edge of the abutment member when the sections of the housing are assembled with the armature assembly therein to hold the abutment member firmly against the electromagnet, the spring member functioning when seated against the held abutment member to exert pressure through the sleeve against the stack, the sleeve of ceramic material preventing a direct transfer of heat and electricity from the stack to the armature and spring member.

2. In a pile regulator having a stack of discs of resistance material and an electromagnet disposed for operation to control the pressure applied to the stack, the combination comprising, a circular abutment member having a central opening therein and having at least a portion of one of its surfaces inclined inwardly from adjacent its outer edge towards the central opening, an ar-

mature disposed in the central opening of the abutment member, a diaphragm disposed to be carried by the armature and extending outwardly therefrom along the other side of the abutment member to adjacent the outer edge thereof, a sleeve of ceramic material disposed between the armature and the stack, a spring member disposed to be carried by the armature with an end of the spring member extending therebeyond along said one surface of the abutment member to seat against the inclined surface thereof, means for securing the spring member, diaphragm, sleeve and armature together as an integral assembled unit with the abutment member disposed between the diaphragm and the spring member, a sectionalized housing for the electromagnet, one section of the housing being carried at an end of the stack and being disposed to encompass the armature assembly and abutment member, a flange carried internally of said one section, and means for securing the sections of the housing in assembled relation with the electromagnet, armature and abutment member therein, the flange of said one section being disposed to seat against the outer edge of the abutment member to hold it firmly against the electromagnet within the housing, the spring member functioning when seated against the held abutment member to exert pressure through the sleeve against the stack, the sleeve of ceramic material preventing a direct transfer of heat and electricity from the stack to the armature and spring member.

3. In a pile regulator having a stack of discs of resistance material and an electromagnet disposed for operation to control the pressure applied to the stack, the combination comprising, a circular abutment member having a central opening therein and having at least a portion of one of its surfaces inclined inwardly from adjacent its outer edge towards the central opening to form mutually inclined surfaces thereon, an armature assembly including an armature disposed in the central opening of the abutment member, a diaphragm disposed to be carried by the armature and extending outwardly therefrom along the other side of the abutment member to adjacent the outer edge thereof, a sleeve of ceramic material disposed between the armature and the stack, a spring member of star form having a central opening therein for receiving the sleeve, the spring member being disposed to be carried by the armature with the rays of the spring member extending therebeyond along said one surface of the abutment member to seat against the mutually inclined surface thereof, means for securing the spring member, diaphragm, sleeve and armature together as an integral assembled unit with the abutment member disposed between the diaphragm and the rays of the spring member, a sectionalized housing for the electromagnet, one section of the housing being carried at an end of the stack and being disposed to encompass the armature assembly and abutment member, and a flange carried internally of said one section disposed to seat against the outer edge of the abutment member when the sections of the housing are assembled with the armature assembly therein to hold the abutment member firmly against the electromagnet, the spring member functioning when seated against the held abutment member to exert pressure through the sleeve against the stack, the sleeve of ceramic material preventing a direct transfer of heat and electricity from the stack to the armature and spring member.

4. In a pile regulator having a stack of discs of resistance material and an electromagnet disposed for operation to control the pressure applied to the stack, the combination comprising, a circular abutment member having a central opening therein and having at least a portion of one of its surfaces inclined inwardly from adjacent its outer edge towards the central opening to form mutually inclined surfaces thereon, an armature assembly including an armature disposed in the central opening of the abutment member, a diaphragm disposed to be carried by the armature and extending outwardly therefrom along the other side of the abutment member to adjacent the outer edge thereof, a cylindrical body of ceramic material disposed between the armature and the stack, the cylindrical body having a shoulder flange disposed thereabout, a spring member of star form having a central opening therein for receiving the cylindrical body, the spring member being disposed to be carried by the armature with the rays of the spring member extending therebeyond along said one surface of the abutment member to seat against the inclined surface thereof, a plate member disposed about the cylindrical body to seat upon the shoulder flange thereof, means for securing the plate member, spring member, diaphragm, cylindrical body and armature together as an integral assembled unit with the abutment member disposed between the diaphragm and the rays of the spring member, a sectionalized housing for the electromagnet, one section of the housing being carried at an end of the stack and being disposed to encompass the armature assembly and abutment member, and a flange carried internally of said one section disposed to seat against the outer edge of the abutment member when the sections of the housing are assembled with the armature assembly therein to hold the abutment member firmly against the electromagnet, the spring member functioning when seated against the held abutment member to exert pressure through the cylindrical body against the stack, the cylindrical body of ceramic material preventing a direct transfer of heat and electricity from the stack to the armature and spring member.

5. In a pile regulator having a stack of discs of resistance material disposed between a fixed pressure plate and a movable pressure plate and an electromagnet disposed for operation to control force applied to the movable pressure plate and thereby control the pressure applied to the stack, the combination comprising, a circular abutment member having a central opening therein and having at least a portion of one of its surfaces inclined inwardly from adjacent its outer edge towards the central opening to form mutually inclined surfaces thereon, an armature assembly including an armature disposed in the central opening of the abutment member, a diaphragm disposed to be carried by the armature and extending outwardly therefrom along the other side of the abutment member to adjacent the outer edge thereof, a sleeve of ceramic material disposed to seat against the armature and to carry the movable pressure plate, a spring member having a central opening therein for receiving the sleeve, the spring member being disposed to be carried by the armature with the ends of the spring member extending therebeyond along said one surface of the abutment member to seat against the mutually inclined surfaces thereof, means for securing the spring member, diaphragm, sleeve and armature together as an

integral assembled unit with the abutment member disposed between the diaphragm and the spring member, a sectionalized housing for the electromagnet, one section of the housing being carried at the end of the stack adjacent the movable pressure plate and being disposed to encompass the armature assembly and abutment member, and a flange carried internally of said one section disposed to seat against the outer edge of the abutment member when the sections of the housing are assembled with the armature assembly therein to hold the abutment member firmly against the electromagnet, the spring member functioning when seated against the held abutment member to exert pressure through the sleeve and pressure plate carried thereby to compress the stack, the sleeve of ceramic material preventing a direct transfer of heat and electricity from the stack and movable pressure plate to the armature and spring member.

6. In a pile regulator having a stack of discs of resistance material disposed between a fixed pressure plate and a movable pressure plate and an electromagnet disposed for operation to control force applied to the movable pressure plate and thereby control the pressure applied to the stack, the combination comprising, a circular abutment member having a central opening therein and having at least a portion of one of its surfaces inclined inwardly from adjacent its outer edge towards the central opening to form mutually inclined surfaces thereon, an armature assembly including an armature disposed in the central opening of the abutment member, a diaphragm disposed to be carried by the armature and extending outwardly therefrom along the other side of the abutment member to adjacent the outer edge thereof, a sleeve of ceramic material disposed to seat against the armature and to carry the movable pressure plate, a spring member having a central opening therein for receiving the sleeve, the spring member being disposed to be carried by the armature with the ends of the spring member extending therebeyond along said one surface of the abutment member to seat against the mutually inclined surfaces thereof, means for securing the spring member, diaphragm, sleeve and armature together as an integral assembled unit with the abutment member disposed between the diaphragm and the spring member, a sectionalized housing for the electromagnet, one section of the housing being carried at the end of the stack adjacent the movable pressure plate and being disposed to encompass the armature assembly and abutment member, a flange carried internally of said one section, and means for securing the sections of the housing in assembled relation with the electromagnet, armature and abutment member therein, the flange of said one section being disposed to seat against the outer edge of the abutment member to hold the abutment member firmly against the electromagnet within the housing, the spring member functioning when seated against the held abutment member to exert pressure through the sleeve and pressure plate carried thereby to compress the stack, the sleeve of ceramic material preventing a direct transfer of heat and electricity from the stack and movable pressure plate to the armature and spring member.

7. In a pile regulator having a stack of discs of resistance material disposed between a fixed pressure plate and a movable pressure plate and an electromagnet disposed for operation to con-

trol force applied to the movable pressure plate and thereby control the pressure applied to the stack, the combination comprising, a circular abutment member having a central opening therein and having at least a portion of one of its surfaces inclined inwardly from adjacent its outer edge towards the central opening to form mutually inclined surfaces thereon, an armature assembly including an armature disposed in the central opening of the abutment member, a diaphragm disposed to be carried by the armature and extending outwardly therefrom along the other side of the abutment member to adjacent the outer edge thereof, a cylindrical sleeve of ceramic material disposed to seat against the armature and to carry the movable pressure plate, the sleeve having a shoulder flange thereabout, a spring member of star form having a central opening therein for receiving the sleeve, the spring member being disposed to be carried by the armature with the rays of the spring member extending therebeyond along said one surface of the abutment member to seat against the mutually inclined surfaces thereof, a plate member disposed about the sleeve to seat upon the shoulder flange thereof, means for securing the plate member, spring member, diaphragm, sleeve and armature together as an integral assembled unit with the abutment member disposed between the diaphragm and the rays of the spring member, a sectionalized housing for the electromagnet, one section of the housing being carried at the end of the stack adjacent the movable pressure plate and being disposed to encompass the armature assembly and abutment member, a flange carried internally of said one section, and means for securing the sections of the housing in assembled relation with the electromagnet, armature and abutment member therein, the flange of said one section being disposed to seat against the outer edge of the abutment member to hold the abutment member firmly against the electromagnet within the housing, the spring member functioning when seated against the held abutment member to exert pressure through the sleeve and pressure plate carried thereby to compress the stack, the sleeve of ceramic material preventing a direct transfer of heat and electricity from the stack and movable pressure plate to the armature and spring member.

50

8. In a pile regulator having a stack of discs of resistance material and an electromagnet disposed for operation to control the pressure applied to the stack, the combination comprising, an abutment member having an inclined surface disposed upon the electromagnet, an armature assembly for the electromagnet, the armature assembly including an armature, an insulating member disposed between the armature and the stack, a spring member disposed to be carried by the armature with an end of the spring member in engagement with the inclined surface of the abutment, a diaphragm disposed to be carried by the armature and extending outwardly therefrom along the other side of the abutment member to adjacent the outer edge thereof, and means for holding the spring member, insulating member, diaphragm and armature together as an integral unit whereby the spring member seated against the abutment exerts pressure through the insulating member against the stack, a sectionalized housing for the electromagnet, one section of the housing being carried at an end of the stack and being disposed to encompass the armature assembly and abutment member, a flange carried internally of said one section, and means for securing the sections of the housing in assembled relation with the electromagnet, armature and abutment member therein, the flange of said one section being disposed to seat against the outer edge of the abutment member to hold the abutment member and diaphragm firmly against the electromagnet within the housing.
